UNITED STATES PATENT OFFICE.

JAMES BERRY AND DAVID T. ODINEAL, OF LEXINGTON, VIRGINIA.

ILLUMINATING ATTACHMENT FOR TELEPHONES.

1,150,413.

Specification of Letters Patent. Patented Aug. 17, 1915.

Application filed February 6, 1915. Serial No. 6,621.

To all whom it may concern:

Be it known that we, JAMES BERRY and DAVID T. ODINEAL, citizens of the United States of America, and residents of Lexington, in the county of Rockbridge and State of Virginia, have invented certain new and useful Improvements in Illuminating Attachments for Telephones, of which the following is a full and clear specification, reference being had to the accompanying drawings, in which—

Figure 1 is a side elevation of a subscriber's outfit of the desk type with our invention applied thereto; Fig. 2 a vertical sectional view taken on the line 2—2 of Fig. 1; Fig. 3 a front elevation of a subscriber's outfit of the wall type provided with our invention; and Fig. 4 a view of a modified form of the switch plug.

The object of this invention is to provide a simple attachment to a telephone subscriber's outfit which when the receiver is removed from its hook and the hook is thus free to rise as usual, a lighting circuit will be automatically closed to thereby illuminate the vicinity of the subscriber's outfit, our invention being particularly intended for use in booths and other dark places where it is desirable to have temporary illumination either before or after the receiver is removed from its hook, to enable the user of the telephone to make pencil memoranda, examine the telephone directory, etc., the construction being such that when the receiver is returned to its hook the circuit closer will be automatically opened to thus break the circuit and extinguish the light or lights and thereby avoid waste of current, as more fully hereinafter set forth.

In the drawings, α designates a suitable support or receptacle which is adapted to be clamped to the standard of a desk outfit by a clamp β , as shown in Fig. 1, or which may be fastened in any suitable manner to the wall outfit, as shown in Fig. 3. This receptacle or support is fastened rigidly directly under the receiver hook c of the telephone outfit, this hook being arranged to normally rise, as usual, when the receiver is removed therefrom.

Normally pressing upwardly against the under side of the hook is a rod δ which is

preferably provided with a laterally extending finger piece e at its upper end. The lower part of this rod extends into the receptacle α and is attached to a spring f which normally tends to press upwardly against the hook. The extreme lower end of this rod works between a pair of spring contacts g which are included in an electric circuit h containing a lamp or lamps i and connected to the usual wires j of the main, the arrangement being such that when the circuit between the contacts g is closed the lamp or lamps will be in circuit with the usual city or local lighting system. The circuit closing rod d is provided with insulation material k at a point where the insulation will separate the contact springs while the rod d is in its usual position. It will be observed that when the receiver is removed from the hook and the hook is allowed to rise, the spring f will cause the rod d to rise and bring the metallic part of the rod below the insulation into contact with the contacts g and thus complete the circuit, and it will be also observed that in case the user of the telephone desires to obtain illumination before he removes the receiver from the hook he may readily accomplish this by simply pressing down with his finger on the finger piece e to bring the metallic part of the rod to a point above the insulation into contact with the contacts g . In other words, it will be seen that whether the rod be pushed downwardly or be allowed to spring upwardly, the circuit will be completed and the lamp or lamps lighted, so that the user may have illumination before he starts to use the telephone or may simply obtain it automatically when he removes the receiver from the hook.

In Fig. 2 the contacts are arranged so that they bear upon the insulation material, but it will be observed that instead of insulation material the push pin may be reduced in diameter at a neutral point in its length, as shown in Fig. 4, so that it will avoid contact entirely with the contacts when in neutral position.

Having thus described our invention, what we claim is:

The combination with a subscriber's telephone outfit of a lighting circuit and means

whereby when the receiver is removed from its hook the lighting circuit will be closed, said means consisting of a circuit closing rod normally tending to rise and so arranged that it normally presses upwardly against the receiver hook, said rod being capable of being pushed down by hand to temporarily close the circuit before the receiver is removed from the hook, if desired.

In testimony whereof we hereunto affix our signatures in the presence of two witnesses this 4th. day of February 1915.

JAMES BERRY.
DAVID T. ODINEAL.
